UNITED STATES PATENT OFFICE.

SIMEON ASBERRY WARE, OF DANBURG, GEORGIA.

PLOW.

SPECIFICATION forming part of Letters Patent No. 292,390, dated January 22, 1884.

Application filed October 12, 1883. (No model.)

To all whom it may concern:

Be it known that I, SIMEON ASBERRY WARE, of Danburg, in the county of Wilkes and State of Georgia, have invented a new and useful 5 Improvement in Plows, of which the following is a full, clear, and exact description.

Reference is to be had to the accompanying drawings, forming a part of this specification, in which similar letters of reference indicate 10 corresponding parts in all the figures.

Figure 1 is a side elevation of my improved plow, the detachable part of the beam being removed. Fig. 2 is a plan view of the same. Fig. 3 is a rear elevation of the same, the 15 handles being shown in section through the line *x x*, Fig. 1. Fig. 4 is a side elevation of the detachable part of the plow-beam. Fig. 5 is a side elevation of the root-cutter. Fig. 6 is a sectional plan view taken through the 20 root-cutter, the plow-beam, and the plow.

The object of this invention is to promote convenience in adjusting plows and efficiency in the operation of the said plows.

The invention consists of the detailed construction and combination of parts, substantially as hereinafter fully set forth and claimed. 25

A represents the plow-beam, the forward end of which is extended upward, and has three (more or less) holes, A', formed through 30 it to receive the hook of the draft-connection B. The hook of the connection B is so formed that it can readily put in and taken out when swung back over the plow-beam, but cannot be put in or taken out when in a working position. 35

The double-tree or whiffletree is designed to be attached to the connection; and the point of draft attachment can be raised or lowered by moving the connection from one 40 to another of the holes A' in the said plow-beam.

To the opposite sides of the middle part of the plow-beam A are secured by a bolt, C, the forward ends of the handles D. The handles D are supported at the required elevation by the brace-bar E, which is bent into triangular form, and its ends are secured to the opposite sides of the plow-beam A at the upper end of its bend by a bolt, F. In the 45 brace E, at the upper ends of its arms, are formed two or more holes, G, to receive the 50

bolts H, by which the said brace is secured to the handles D, and in the said handles D are formed three (more or less) holes, I, to receive the fastening-bolts H. With this construction the handles can be adjusted higher or lower as the height of the plow may require. The brace E can be placed at the inner or outer side of the handles, and will prevent the handles from being spread too wide 55 apart when the said brace is swung forward to raise the said handles.

In the bend of the plow-beam A is formed an offset, J, and to the lower part of the said beam is secured, by bolts K, a plate, L, made 60 to correspond in shape with the said lower part of the said beam. Upon the inner side of the lower end of the plate L is formed a projection, M, of a thickness equal to the width of the offset J, so that when the said plate L is bolted to the plow-beam a slot will be formed to receive the bolt N, that fastens 65 the plow O to the plow-beam. This construction allows a longer or shorter plow to be used, and also allows the plow to be moved 70 down as it wears.

To the side of the lower end of the beam A is bolted a landside, P, to give steadiness to the plow when being used, and which is slotted to receive the fastening-bolts, so that it 75 can be adjusted as may be required. When required, the landside P can be detached and a blade or cutter, Q, secured, by the bolts K, to the side of the beam, to cut roots that may be in the soil, and which would otherwise 80 prevent the plow from being used.

Having thus described my invention, I claim as new and desire to secure by Letters Patent—

In a plow, the beam A, having the offset J cast in one piece therewith, and the plate L, 90 having the projection M cast therewith, the projection M resting against one side of the beam A, and the plate L resting against the offset J and bolted to the beam A, in combination with the plow O and bolt N, fastened 95 between the plate L and beam A, substantially as shown and described, and for the purpose set forth.

SIMEON ASBERRY WARE.
